UNITED STATES PATENT OFFICE.

JOSEPH GOODMAN AND WILLIAM A. SOMERS, OF HAMDEN, CONNECTICUT, ASSIGNEES
TO THE MT. CARMEL MANUFACTURING COMPANY, OF HAMDEN, CONNECTICUT,
A CORPORATION OF CONNECTICUT.

SHADE ROLLER.

Application filed June 13, 1922. Serial No. 567,930.

To all whom it may concern:

Be it known that we, JOSEPH GOODMAN and WILLIAM A. SOMERS, citizens of the United States, residing at Hamden, in the county of New Haven and State of Connecticut, have invented certain new and useful Improvements in Shade Rollers, of which the following is a specification, reference being had therein to the accompanying drawings.

This invention relates to shade rollers, its principal object being to provide a roller that will be noiseless.

Among other aims and objects of the invention may be recited the provision of a device of the character mentioned with a view to compactness, in which the number of parts are few, the construction simple, the cost of production small and efficiency of operation high.

The improvements in the details and arrangement of parts will be apparent from an inspection of the accompanying drawings, in connection with the description herein-after contained and wherein a preferred embodiment of the invention is disclosed for the purpose of imparting an understanding of the same.

In the drawings wherein like characters of reference indicate corresponding parts in the several views;

Figure 1 shows our invention in side elevation, some parts being broken away and others in section;

Figure 2 is a sectional end view thereof, the parts in section being taken generally upon line 2-2 of Figure 1;

Figure 3 is a view similar to that shown in Figure 2, but one of the pawls therein is in a different relative position;

Figure 4 is a detailed end elevation of the head member; and

Figure 5 is a fragmentary plan view of one end of the rod and a pawl in engagement therewith.

In the drawings, 10 designates the roller which is preferably made of sheet metal and lined with felt 11, or the like, to deaden any noise that might result from the striking of the parts thereagainst; and 12 is a rod having a notch 13 therein near one end and is threaded or otherwise permanently secured in a bracket 14 attached to the wall or frame of the window, as is usual. The notch 13

has a locking face 15 which is in a vertical plane when the bracket 14 is fixed in position and a clearing face 16 at an angle thereto. The journal collars 17-17 which are secured to a felt or fibre disk 18 support this rod at its inner end.

Rotatably mounted upon a bushing 20 upon the rod 12 and held against endwise movement in one direction by a collar 21 thereon is the head member 19 having a recess or depression 22 in the inner face thereof. This recess or depression 22 has two parallel sides 23 and rounded ends 24, these latter upon the opposite sides of the recess being of substantially the same diameter as the inside of the roller 10 and form means for centering and supporting the same in relation thereto. A greater number of pawls may be used if desired.

Lying within the recess 22 are the two pawls 25-25, these being substantially L-shaped and having a straight bar portion 26 and an inwardly turned tooth portion 27, this latter having a straight inner or locking face 28 and an angular outer or clearing face 29.

The open end of the head member 19 is covered by a cap 30 having an inwardly turned flange 31 thereon that projects over the flange 32 of the head member 19 and is secured thereto and to the roller 10 so that the same become a single unitary structure.

A coil spring 33 encircles the rod 12, being fixed thereto at its inner end and at its outer end to the hub 34 of the head member 19. The roller 10 is provided at the end thereof opposite to the head member 19 with a head member 35, which is covered by a cap 36 secured thereto and rotatable upon a stud 37 fixed in the bracket 38. To prevent rattling of the parts at their end, we have inserted a spring 39 in the recess 40 in the head member 35, which bears against the stud 37.

The pawls 25 are mounted within the recess 22 for right line movement parallel with each other and the tooth portion of the upper pawl when the recess 22 is vertical or substantially so, tends to move by gravity toward the axis of the rod 12, but is held away therefrom by centrifugal force when the roller is rotated rapidly.

If the roller is at rest the tooth 27 of one

of the pawls 25 is in the notch 13 substantially as shown in Figure 2, the locking face 28 thereon and the locking face 15 of the notch 13 being held in contact with each other by the tension of the coil spring 33.

When the roller is rotated when unreeling the curtain, the clearing face 16 of the notch 13 by reason of its engagement with the clearing face 29 of the tooth 27 lifts the pawl 25 out of engagement with the notch 13 and allows the roller to rotate. If the speed of rotation of the roller is sufficient to keep the pawls in their outermost position, the teeth thereon will pass the notch 13 without engagement therewith, but if the movement is slow, such as is usual when desired to fix the curtain in an adjusted position, the uppermost of the pawls 25 will drop by gravity into said notch and hold the roller against further rotation.

The straight bar portions 26 of each of the pawls are of such length as to overlap the tooth portion of the other pawl substantially as shown in Figure 2, thus one pawl reinforces the other and prevents relative lateral movement thereof.

With a shade roller constructed substantially as shown herein and described, the roller can be held in a fixed position at each one-half revolution thereof and as there are no pivoted pawls or ratchet wheels as is common in some types of shade rollers, the same is absolutely noiseless and therefore especially adapted for use where the slightest noise is objectionable, such as in motor vehicles or the like.

Having described our invention, what we claim is:

1. In a device of the character described; a roller; a head member connected therewith; a bracket; a rod secured in said bracket and held against rotation relatively thereto and having a notch therein; a plurality of pawls having a constant sliding contact with each other, each of said pawls having a tooth thereon adapted to drop into said notch and hold said roller against rotation in one direction and to be released from said notch by the rotation of said roller when moved in the opposite direction, the toothed portion of one of the pawls being moved away from the toothed portion of the other of said pawls by centrifugal force during the rotation of the head member.

2. In a device of the character described; a roller; a head member connected therewith; a bracket; a rod secured in said bracket and held against rotation relatively thereto and having a notch therein; a plurality of substantially L-shaped pawls having a constant sliding contact with each other, each pawl having a tooth thereon adapted to drop into said notch and hold the roller against rotation in one direction and to be released from said notch by the rotation

of said roller when moved in the opposite direction, the toothed portion of one pawl being moved away from the toothed portion of the other pawl by centrifugal force during the rotation of the head member.

3. In a device of the character described; a roller; a head member connected therewith; a bracket; a rod secured in said bracket and held against rotation relatively thereto, having a notch therein; a plurality of independently movable pawls, actuated by gravity and centrifugal force toward and away from each other but retaining a constant sliding contact with each other, each pawl holding the other pawl against movement when one of the pawls is in engagement with said notch.

4. In a device of the character described; a roller; a head member connected therewith having a recess therein with two substantially parallel walls; a bracket; a rod secured in said bracket and held against rotation relatively thereto, having a notch therein; a plurality of pawls movably mounted within said head member and adapted to drop into said notch and hold said roller against rotation in one direction and to be released from said notch by the rotation of said roller when moving in the opposite direction; said pawls being so arranged that a portion of one of said pawls is in constant sliding contact with one of the sides of said recess and a portion of the other of said pawls is in contact with the opposite wall thereof.

5. In a device of the character described; a roller; a head member connected therewith having a recess therein with two substantially parallel walls; a bracket; a rod secured in said bracket and held against rotation relatively thereto, having a notch therein; a plurality of pawls of less width than said recess movably mounted therein and adapted to drop into said notch and hold said roller against rotation in one direction and to be released from said notch by the rotation of said roller when moving in the opposite direction; said pawls being so arranged that a portion of one of said pawls is in constant sliding contact with one of the sides of said recess and a portion of the other of said pawls is in contact with the opposite wall thereof.

6. In a device of the character described; a roller; a head member connected therewith having a recess therein with two substantially parallel walls; a bracket; a rod secured in said bracket and held against rotation relatively thereto, having a notch therein; a plurality of pawls movably mounted within said recess, each of less width than said recess and held against lateral movement therein by the other of said pawls with which it is in constant contact and moved outwardly in opposite di-

rections from the center of the roller by centrifugal force.

7. In a device of the character described, a roller; a head member connected therewith; a bracket; a rod secured in said bracket and held against rotation relatively thereto, having a notch therein; a plurality of pawls having constant sliding contact with each other movably mounted within 5 said head member in opposite directions by centrifugal force, each of the pawls having a tooth thereon that is adapted to drop into said notch and hold said roller against rotation in one direction and to be released 10 from said notch by the rotation of said roller when moving in the opposite direction, each of said pawls having a substantially straight side portion and an offset tooth portion at one end having one locking face and a clearing 15 face extending therefrom at an angle thereto.

8. In a device of the character described, a roller; a head member connected therewith; a cap covering said head member; a bracket; a rod secured in said bracket and held against rotation relatively thereto, having a notch therein; a plurality of pawls having constant sliding contact with and movable relatively to each other by centrifugal force within said head member and adapted to drop into said notch and hold said roller against rotation in one direction and to be released from said notch by the rotation of said roller when moving in the 20 opposite direction, said roller, head member and cap forming a unitary structure.

9. In a device of the character described, a roller; a head member connected therewith having a recess in one side with two substantially parallel walls and a projection upon the opposite side having similar parallel sides and two round ends, the distance therebetween being substantially the same as that of the inside diameter of said roller by which it is centered; a cap covering one 25 end of said head member and fixed thereto, said roller, head member and cap forming a single unitary structure.

10. In a device of the character described, a roller; a head member connected therewith having a recess in one side with two substantially parallel walls and a projection upon the opposite side having similar parallel sides and two round ends, the

distance therebetween being substantially 55 the same as that of the inside diameter of said roller by which it is centered; a cap covering one end of said head member and fixed thereto, said roller, head member and cap forming a single unitary structure; a 60 rod secured in said bracket and held against rotation relatively thereto, having a notch thereon; a plurality of pawls mounted within said recess movable in opposite directions by centrifugal force and at the same time maintaining a constant sliding contact with each other; and a spring surrounding said rod having connection at one end therewith and at the other end with said head 65 member.

11. A curtain roller comprising rotary and stationary elements; means tending to turn the rotary element; and a pair of pawls carried by the rotary element and actuated independently therein by gravity and centrifugal force toward and away from each other, but retaining a constant sliding contact with each other, said pawls and stationary element being provided with shoulders adapted to co-act to prevent turning of the 75 rotary element in one direction.

12. A curtain roller comprising rotary and stationary elements; means tending to turn the rotary element; two pawls carried within a recess in the rotary element that move away from the center of said element by centrifugal force and at the same time maintaining sliding contact with each other during their entire relative movement, each pawl having a tooth thereon adapted to drop 80 into the notch in said roller and hold the same against movement in one direction.

13. A curtain roller comprising rotary and stationary elements, means tending to rotate the rotary element in one direction, 85 and a plurality of separate relatively movable pawls having constant contact with each other carried by the rotary element and provided with shoulders, said stationary element being provided with a shoulder adapted to coact with the shoulder on any of the pawls to prevent turning of the element in the opposite direction.

In testimony whereof we have hereunto affixed our signatures.

JOSEPH GOODMAN.
WILLIAM A. SOMERS.
